UNITED STATES PATENT OFFICE.

ELIAS D. ROTH, OF FORT COLLINS, ASSIGNOR OF ONE-HALF TO JACOB A. PEARCE, OF BUENA VISTA, COLORADO.

LUBRICATING DEVICE FOR CUTTER-BARS.

SPECIFICATION forming part of Letters Patent No. 295,814, dated March 25, 1884.

Application filed January 24, 1884. (No model.)

To all whom it may concern:

Be it known that I, ELIAS D. ROTH, a citizen of the United States, residing at Fort Collins, in the county of Larimer and State of Colorado, have invented certain new and useful Improvements in Lubricating Devices for Cutter-Bars, of which the following is a specification, reference being had therein to the accompanying drawing.

My invention relates to a lubricator for reapers and mowers, its object being to provide a device for automatically lubricating the working parts of the cutter-bar of same, as will be hereinafter more fully set forth.

15 In the accompanying figure, which is a perspective of my device, A represents a finger-bar of the machine, which is provided at the rear of its upper side with a longitudinal groove, a, in which the cutter-bar B lies and 20 is made to reciprocate.

C C represent the cutters. The rear ends of these cutters are pivoted to the cutter-bar B. They are pivoted also centrally between the finger-bar and an overlying plate, D, as 25 seen at x x.

E represents a cap, which is hinged to the rear of the finger-bar, and which lies over the cutter-bar to shield it, as far as possible, from injury and from dust and dirt.

30 F represents a perforated pipe, which is secured to the cap E, running lengthwise of it, and which connects with a flexible tube, G. The tube G connects with an oil-reservoir, H. This oil-reservoir is secured upon any convenient portion of the frame of the machine, in 35

order that the lubricant contained therein may be readily carried to the working parts of the cutter-bar. The tube G is provided with a suitable cock to regulate or cut off the flow of oil from the reservoir H. The flexible connection to the pipe F allows the cap E to be raised in order that the cutter-bar and its knives may be easily reached for repair or other purposes. The cutter-bar is actuated by the usual pitman or in any of the well-known and usual ways. 45

By this attachment I am enabled to run a machine for any reasonable time without having to stop it for the purpose of "oiling up."

Having thus fully described my invention, what I claim as new, and desire to secure by Letters Patent, is—

1. The perforated pipe F, in combination with the cutting apparatus of a reaper or mower, said pipe being connected to a suitable oil-reservoir, substantially as and for the purpose set forth. 55

2. The hinged cap E, carrying a perforated pipe, F, in combination with the cutting apparatus of a reaper or mower, the same being connected to an oil-reservoir by a flexible connection, substantially as and for the purpose set forth. 60

In testimony whereof I affix my signature in presence of two witnesses.

ELIAS D. ROTH.
